UNITED STATES PATENT OFFICE.

CHARLES L. TRAVIS, OF MINNEAPOLIS, MINNESOTA.

DESIGN FOR A FRAME-COUPING FOR BICYCLES.

SPECIFICATION forming part of Design No. 30,118, dated January 31, 1899.

Application filed October 25, 1897. Serial No. 656,373. Term of patent 14 years.

To all whom it may concern:

Be it known that I, CHARLES L. TRAVIS, a citizen of the United States, residing at Minneapolis, in the county of Hennepin and State 5 of Minnesota, have invented and produced a new and original Design for Frame-Couplings for Bicycles, of which the following is a specification.

My present invention pertains to a new and 10 original design for frame-couplings for bicycles and is clearly shown in the accompanying drawings, wherein—

Figure 1 is a perspective view, and Fig. 2 a side elevation.

15 As shown in the drawings, the leading or material features of my design consist of the flat plate or web A and the curved or rounded

section B, directly connected to the rear end thereof. At the forward end of the plate there is a narrow section C, which is somewhat 20 thicker than the plate or web A and is directly connected to or forms a part of the hanger-barrel D.

Having thus described my invention, what I claim is—

25 The new and original design for a frame-coupling for bicycles, substantially as shown and described.

In witness whereof I hereunto set my hand in the presence of two witnesses.

CHARLES L. TRAVIS.
